UNITED STATES PATENT OFFICE.

HENRY LAFAYETTE PIPPEN, OF WHITAKERS, NORTH CAROLINA.

PEANUT-GLEANER.

972.910.

Specification of Letters Patent. Patented Oct. 18, 1910.

Application filed May 28, 1908. Serial No. 435,498.

To all whom it may concern:

Be it known that I, HENRY L. PIPPEN, a citizen of the United States, residing at Whitakers, in the county of Edgecombe and State of North Carolina, have invented certain new and useful Improvements in Peanut-Gleaners; and I do hereby declare the following to be a full, clear, and exact description of the invention, such as will enable others skilled in the art to which it appertains to make and use the same.

The object of this invention is to improve the construction and increase the efficiency of peanut-gleaners or harvesters of the character exhibited in my Patent No. 887,015, dated May 5, 1908.

My invention will hereinafter be first fully described with reference to the accompanying drawings, which form a part of this specification, and then more particularly pointed out in the appended claims.

In said drawings: Figure 1 is a side elevation of a machine embodying my improvements. Fig. 2 is a longitudinal vertical section of the same. Fig. 3 is a top plan view. Fig. 4 is a perspective view of one of the cross-bars provided with pick-up rakes employed upon an endless carrier of the machine.

The machine exhibited in my former patent may be described, in general terms, as a wheeled vehicle carrying a mounted box or receptacle for peanuts, and an inclined grate extending forwardly and downwardly from said box, said grate composed of a plurality of rods the lower ends of which pass along the ground and rake and scoop up the loose peanuts, and an endless carrier arranged under the grate and having a plurality of transverse rakes whose teeth pass between the grate-bars and are adapted to pick-up the loose peanuts gathered upon the grate and carry them rearwardly upward and deposit them into the said box or receptacle. The same construction of the box, grate and endless carrier with its pick-up rakes is embodied in my improved machine as illustrated in the accompanying drawings.

Referring to said drawings, A denotes the frame of the machine or vehicle, mounted on front supporting wheels B and rear supporting and driving wheels C.

D is the peanut-box or receptacle, having a grate-like bottom composed of rods E, and a grate-like front composed of the rear

downward extensions f of the grate-bars or rods F which constitute the aforesaid inclined grate.

G denotes the side-members of the inclined frame which supports the grate F and endless carrier, the latter consisting of sprocket-chains H, running around sprocket-wheels on shafts I and J, and carrying a plurality of pick-up rakes K which on the upper run and turns of the carrier pass between the grate-bars F, the latter lying upon the cross-bars of the rakes.

As explained in my said former patent, the teeth of the rakes K, as the latter make their forward turn, pass up between the grate-bars F and pick up the peanuts which have been gathered or lodged thereupon; and as the rakes move rearwardly-upwardly with the upper run of the carrier the peanuts caught thereby are carried over the grate and deposited into the box or receptacle D; the teeth of the rakes in making their rear turn passing between the rear vertical extensions f of the grate-bars.

The shaft J is mounted in bearings in the opposite sides of the box D, and the side-bars G, in which the shaft I is mounted, are loosely or pivotally mounted on said shaft J to permit rocking said side-bars G together with the grate-bars F and endless carrier.

For driving the carrier from the shaft or axle C¹ of the rear drive-wheels C, the shaft J is shown having a pinion j meshing with a pinion j¹ on a stub-shaft provided with a sprocket-wheel j² engaged by a sprocket-chain j³ running from a sprocket-wheel j⁴ on the shaft C¹ of the drive-wheels.

For the purpose of throwing the machine in and out of gear, the sprocket-wheel j⁴ is mounted loosely on the shaft or axle C¹, its hub being provided with a clutch-member l which coacts with a clutch-member l¹ splined on the shaft, the two clutch-members being normally held in engagement by the spring l² interposed between the hub of one wheel C and the sprocket-hub. The loose clutch-member l on which the sprocket-wheel j⁴ is mounted has a grooved collar which is engaged by the fork of the throw-out lever M herein described.

As thus far described, the machine herein illustrated is substantially similar to that exhibited in my aforesaid patent, except in substituting the front supporting wheels B for the hold-up slide-bar or drag shown in said patent. I will now describe the novel

features of my improvement applied to or embodied in the present machine.

In advance of the front lower ends of the grate-bars F, there is provided a plow P for 5 the purpose of loosening up the peanuts left in the soil, it being understood that the machine is used more particularly for gleanings loose or scattered peanuts after digging and stacking. The plow-point is provided with 10 rearwardly inclined rods or fingers p. Said plow P is attached to the foot of a goose-neck standard or beam O, the upper main portion of which is forked or bifurcated: and the two arms or branches O¹, O² of the 15 forked beam are pivotally-attached to the opposite side-members of the frame A, by means of pivot bolts o, allowing the goose-neck standard with the plow attached to swing up and down. The plow P is adapt- 20 ed to be raised and lowered by means of a lever R which is mounted or rigidly-attached on one end of a cross-rod or shaft Q journaled in bearings q in the opposite sides of the frame A; said rod or shaft Q having 25 a medial cranked portion Q¹ working in a slot Q² in the plow-beam or provided by means of a low yoke-piece o¹ constructed on the back or top of the plow-beam. The lever R is provided with the usual auxiliary 30 finger-lever r and lock-bolt r¹ adapted to engage a segmental rack R¹ on one of the side-beams of the main frame A.

Lever R is connected by a rod S to one arm of an angle-lever or bell-crank lever T, 35 shown mounted on an upright T¹, the other arm of said angle-lever T being connected by a chain T² or otherwise to the frame G which supports the grate F and endless carrier of pick-up rakes K; whereby lever R 40 communicates motion to angle-lever T for raising and lowering the frame G in order to elevate the front ends of the grate-bars from or lower them upon the ground. Angle-lever T is also connected by a rod N 45 with one arm of another angle-lever M, shown mounted in bracket M¹ near the rear of the machine; the other arm of said angle-lever M being forked and engaging the grooved-collar of the loose clutch-member 50 l, hereinbefore referred to, whereby from lever R the angle-lever M can be operated for throwing the machine in and out of gear with the drive-wheels C. By means of the connections described, one forward 55 shove or throw of lever R will simultaneously raise the plow P, lift the frame of the grate and endless carrier, and throw the machine out of gear.

Behind the rear end of the carrier is a 60 revolving roller U having long teeth or prongs adapted to pass between the teeth of the pick-up rakes K and knock out any pieces of loose vines, grass and other trash that may have been caught by the rakes. 65 This roller, is mounted to revolve in bear-

ings u in opposite sides of the box D, and is driven by a belt V running from a pulley V¹ on shaft C¹ to pulley V² on one end of the roller-shaft.

The belt V is engaged by a belt-tightening 70 pulley W carried by one arm of an elbow lever W¹, which is mounted on the side of box D; the other arm of said lever W¹ being connected by rod X with a lever Y which is mounted on the frame A and provided with a supplemental finger-lever y and lock-bolt y¹ engaging a segment rack Y¹ mounted on the same side of frame A. By means of lever Y the belt-tightener can be controlled for tensioning or releasing the belt. 75

Both levers R and Y, on opposite sides of the frame A, are arranged in convenient range of a driver's seat Z which is mounted on the front of the machine. 80

The machine will be hauled preferably 85 by a two-horse-team, for which the necessary double-tree is shown provided in connection with the tongue A¹, the latter being attached to the pivot-axle of the front wheels B by which the machine is steered. 90

While my invention is primarily adapted for harvesting peanuts, it may also be adapted for harvesting other sub-soil products, and the invention is intended to extend to any use for which the machine may 95 be adapted.

I do not intend to restrict myself to the precise details of construction and arrangement shown, since various modifications may be made within the scope of my invention. 100

Instead of the belt V the trash-separating roller can be driven by a sprocket-chain from the axle C¹, in which case the belt-tightener and associated parts may be 105 omitted.

Having thus described my invention, what I claim as new and desire to secure by Letters Patent of the United States is:

1. In a peanut gleaner, the combination 110 of a wheeled vehicle, a downwardly-forwardly inclined swinging frame, a grate supported thereby, the forward end of said grate adapted to rake peanuts from the ground, an endless conveyer having a plurality of rakes adapted to convey the peanuts over said grate and deliver them, a plow running in advance of the grate adapted to loosen peanuts in the soil, a plow-beam swung from the vehicle-frame, a cross-shaft having a crank connected with said swinging plow-beam, a lifting lever mounted on said shaft, an angle lever having one arm connected with said inclined frame, and a rod connecting the other arm of said angle-lever and said lifting lever, whereby the plow and front end of the grate can be raised and lowered simultaneously. 115

2. In a peanut gleaner, the combination 120 of a wheeled vehicle, a downwardly-for- 125

wardly inclined swinging frame, a grate supported thereby, the forward end of said grate adapted to rake peanuts from the ground, an endless conveyer having a plurality of rakes adapted to convey the peanuts over said grate and deliver them, a plow running in advance of the grate adapted to loosen peanuts in the soil, driving connections for running said conveyer from the supporting drive-wheels of the machine, said driving connections including a clutch, a plow running in advance of the grate, a swinging plow-beam, a cross-shaft having a crank connected to said plow-beam, a lifting-lever mounted on said shaft, an elbow-lever having one arm connected with said

inclined frame, a rod connecting its other arm with said lifting lever, another angle-lever having one arm operating a clutch-throw, and a rod connecting the other arm 20 of the latter angle-lever with the first-mentioned angle-lever, whereby the machine can be thrown out of gear and the grate and plow raised simultaneously by means of said lifting-lever.

25

In testimony whereof I affix my signature, in presence of two witnesses.

HENRY LAFAYETTE PIPPEN.
